FORCED AIR VENTILATING HEATERS

Thurman A. Pelsue and Lloyd W. Braa, Denver, Colo., assignors to The Morrison-Pelsue Co., Denver, Colo., a partnership

Application May 27, 1954, Serial No. 432,863

2 Claims. (Cl. 126—110)

This invention relates to heaters and more particularly to forced air ventilating heaters.

Subsurface installations of power lines, telephone cables, natural gas and sewer lines has become common practice for the public utilities and telephone companies. Installation of these facilities in underground tunnels has the advantage of protecting them from surface weather conditions which frequently disrupt the service over wide areas. Underground temperatures do not fluctuate over as wide a range as those on the surface and convenient access to the facilities is provided by manholes on the surface. A number of extremely hazardous conditions arise in connection with these subsurface facilities which would not be found in surface installations; therefore, a variety of special safety precautions are necessary for the protection of the public and property located near these installations; and more particularly, for personnel whose duty it is to inspect and repair these facilities.

Underground ventilation is a major problem which cannot be solved by merely leaving the access opening uncovered and depending upon natural ventilation from the surface. Some means for supplementing natural ventilation with forced fresh air ventilation is an absolute necessity in most cases. Quite often the occasion which requires repair of the underground facilities has produced an explosive gas mixture which is extremely hazardous. Efficient forced air ventilation will of course supply enough fresh air to reduce the relative concentrations of the components to the point where an explosive mixture no longer exists, thereby providing a safe atmosphere in which to work. Extreme care must be taken, however, that the apparatus for supplying the ventilation is located where it will not in itself ignite the explosive mixture.

It is also quite common to find noxious, although non-explosive concentrations of gases existing in underground workings. For instance, an insufficient concentration of oxygen may be present due to underground combustion, so that a noxious concentration of carbon monoxide and carbon dioxide may exist and be undetected due to their odorless physical characteristics. Although gas testing equipment is provided for testing the concentration of gases in underground workings before they are entered, there is always the possibility that these precautions will not be taken and serious injury or death might result.

Hazardous conditions such as those outlined in preceding paragraphs, although not existing at the time the underground workings are entered, may be brought about by the ventilating or heating equipment used. In the case of blowers, if the exhaust fumes from the engine are permitted to remain in the underground workings, a noxious concentration of gases may be created. Ordinary space heaters, whether or not connected with a blower, have the same limitations and cannot be used underground because the burner quickly exhausts the oxygen and the exhaust gases of combustion are quite dangerous.

The problem of heating subsurface installations and

2

also certain other types, such as the aerial tents erected by linemen on telephone poles, raise additional problems. The tunnels are most often damp and extremely uncomfortable for the workmen, especially if the outside air is also cold. Cold, damp underground working conditions have an adverse effect upon the health of the workmen as well as causing decreased efficiency. Apparatus to heat such installations and thereby make them more comfortable requires several important features not found in the conventional space heater or blower. Open flames or even sparks cannot be tolerated underground because of the chance of causing a dangerous explosion. The danger of fire while using conventional heating equipment in telephone linemen's tents is also of great importance.

The principal object of the present invention is, therefore, to provide a forced air ventilating heater which may be located above ground and used to force warm, clean air into underground tunnels for the convenience and comfort of workmen without danger of detonating any explosive gas mixtures which may be present or introducing any explosive or noxious mixtures into the tunnels.

Another object of the present invention is to blow out by forced ventilation any explosive or noxious gas mixtures which might exist in underground workings.

A further object of the invention is to provide a heater which, by means of duct work may be used to heat linemen's aerial tents located above the ground which might otherwise catch on fire causing serious damage to equipment and injury to personnel.

Other objects will be in part apparent and in part pointed out specifically hereinafter in connection with the description of the drawing which follows, and in which:

Figure 1 is a side elevation of the forced air ventilating heater of the present invention showing it connected to a tank of liquid petroleum gas;

Figure 2 is an end elevation looking in the direction of arrow 2 of Figure 1 having portions broken away to expose the squirrel-cage blower;

Figure 3 is a diagrammatical view showing the manner in which the ventilating heater is used to force warm ventilated air into underground facilities;

Figure 4 is a section taken along line 4—4 of Figure 2 showing the burner assembly, heat exchanger, and blower;

Figure 5 is a section taken along line 5—5 of Figure 4 showing the construction of the burner assembly and heat exchanger; and,

Figure 6 is a transverse section taken along line 6—6 of Figure 4 showing the combustion chamber.

Referring now in particular to Figures 1 and 2 of the drawing, reference numeral 10 designates an engine of a conventional type provided with an automatic recoil starter 12, which has been adapted for either liquid petroleum gas or gasoline operation. Gasoline tank 14 provides fuel for emergency operation of the engine as the prime source of engine fuel for the engine is liquid petroleum gas taken from tank 16 through the conventional flexible liquid gas hose 18 into fuel line 20. Auxiliary outlet valve 22 is provided in one end of the fuel line for use in operating auxiliary equipment, such as burners for lead pots and the like. A conventional spring loaded diaphragm type pressure regulator 24 is connected in the fuel line. The main fuel line 20 branches to form engine fuel line 26 and burner fuel line 28. Engine fuel line 26 is provided with an automatic zero governor 30 to automatically shut off the flow of fuel into propane carburetor 32 when the engine stops. Burner valve 34 is connected in the burner fuel line 28 in order to supply fuel to the burner for wintertime operation. An automatic gas shut off valve 36 shuts off the burner when it is not lit. Frame 38 supports the engine and related

parts. Housing 40 is supported on the frame and contains the squirrel cage blower 42, the heat exchanger 44, and the burner, combustion chamber, and related parts which will be described in detail in connection with Figures 4, 5, and 6. Blower wheel 46 is operatively connected for rotation on engine shaft 48. The squirrel cage blower draws air from the atmosphere in through air intake 50 in the housing. Handle 52 is secured to the blower housing and engine by means of bracket 54 for convenience in carrying the heater.

With particular reference to Figures 4 and 5, it will be seen that the combustion chamber 56 containing the burner assembly 58 is connected to the heat exchanger 44 in such a way that the hot flue gases pass up from the burner assembly into the combustion chamber, through the heat exchanger, and out through the burner flue 60 thereby heating the air in the ventilating air space 62. Blower housing 64, however, cooperates with the blower wheel to direct the cold incoming fresh air against the hot surfaces of the combustion chamber and heat exchanger where it is heated before being exhausted through air discharge 66.

The burner assembly 58 is located at the lower end of the combustion chamber 56 wherein burner 68 is connected to the burner fuel line 28. Conventional forced air inspirating type burners containing three orifices have been shown in Figure 5 of the drawing although a number of other well known types are suitable. An electric ignitor 70, which may operate off a constant spark taken from the engine magneto has been shown in Figure 4 as the means for lighting the burner. A thermocouple 72 is positioned above the burner and connected to automatic burner shut off valve 36. Stainless steel tubes 74 positioned above the burner orifices complete the burner assembly. The upper end of the combustion chamber connects with the interior of the heat exchanger which consists of a series of laterally extending passages 76 communicating with one another and with the combustion chamber and burner flue, but closed off from the ventilating air space 62 by wall portions 78. Heat is transferred through the wall portions from the hot flue gases to the ventilating air within ventilating air space 62 as it passes over these walls prior to being discharged through air discharge 66. Burner flue 60 is protected by chimney 80 to prevent persons being burned on contact with the hot flue. A viewing port 82 is provided in the combustion chamber for inspection of the burner assembly.

In Figure 6 will be seen the manner in which the combustion chamber 56 is fastened to the housing 40 by means of combustion chamber housing 84. Viewing ports 86 in alignment with viewing port 82 of the combustion chamber are provided in the combustion chamber housing 84 and housing 40. A cover plate 88 is mounted for pivotal movement within housings 84 and 40 in position to cover the viewing ports 86. Lever 90 operates the cover plate.

Referring now to the diagram shown in Figure 3, it will be seen that with an air hose 92 connected over air discharge 66 with its open end extending down into a tunnel through access opening 94 on the surface, fresh, warm air may be supplied to the subsurface installations. The ventilating heater is, of course, positioned above ground where the noxious exhaust fumes from the engine 10 and the flue gases passing out through burner flue 60 are exhausted into the atmosphere where they can do no harm. With the heater itself located above ground, there is no possibility of sparks or flames developed in the heater causing explosions. The high temperatures developed within the combustion chamber, burner assembly, and heat exchanger are adequate to heat the cold incoming air even under extreme weather conditions to a point where it will be discharged into the tunnel as warm healthful air contributing to the comfort and well-being of personnel working therein. The bottom of the combustion chamber shell 56 is notched as shown

most clearly in Fig. 4 to provide an opening 100 to supply primary air to the burner assembly. By reason of the fact that the blower while operating maintains the interior of the casing under a positive pressure, primary air will be forced through the burner assembly upwardly in the combustion chamber 56 to supply a sufficient quantity of air for proper combustion of the fuel. However, the burner unit is effectively isolated from the ventilating air cavity since the forced draft will prevent fuel from entering the ventilating air cavity even under conditions in which the burner is not ignited.

It is to be understood that the present invention is not intended to be limited in any respect to the various safety devices which have been illustrated and described in connection with the accompanying drawing which do not directly contribute to the delivery of non-poisonous air into the desired location. These elements while valuable and necessary to the safe operation of the engine and fuel lines do not form a part of the present invention. Also, many other suitable prime movers such as electric motors and other types of engines may be used with equal facility for the operation of the blower. Such features are intended as being merely illustrative of one manner in which a ventilating heater of the type described herein may be constructed, and it is apparent that many modifications might be made within the skill of the ordinary mechanic while retaining the basic invention.

Having thus described the present invention in detail in connection with the accompanying drawing, it will be seen that the many useful objects for which it was designed have been achieved; and therefore, we claim:

1. A forced air ventilating heater comprising a base, a housing mounted on said base consisting of a generally rectangular casing including opposite side walls, end walls, 35 a top wall and a bottom wall, one of said side walls having an opening therein adjacent one of said end walls and forming a blower inlet opening, a prime mover mounted on said base and having a drive shaft projecting into said housing through the opposite side wall, a blower 40 wheel fixed to said drive shaft within said housing, an involute blower wheel shroud fixed to and extending between said side walls in surrounding relation to said blower wheel and encompassing said inlet opening and discharging along the bottom of said housing toward the 45 opposite end wall, a shell forming an elongate cylindrical combustion chamber disposed within said housing adjacent said opposite end wall, said combustion chamber shell resting at its lower end on said bottom wall and being of a diameter substantially less than the distance 50 between said side walls so as to be spaced therefrom and from the adjacent end wall to allow the circulation of air therearound, a burner mounted on said bottom wall for directing fuel upwardly through said combustion chamber shell, means adjacent said burner for igniting 55 said fuel, said combustion chamber shell having an opening therein adjacent said burner for the supply of combustion air thereto, the upper end of said combustion chamber extending above the uppermost portion of said blower wheel shroud, a series of interconnected, vertically spaced, substantially horizontally disposed heat exchanger ducts fixed to and in communication with said upper end of the combustion chamber and with the major portion thereof extending laterally therefrom over said shroud but in spaced relation thereto and to the top 60 and side walls, said top wall having an opening therein above said combustion chamber, a flue carried by said heat exchanger and extending outwardly of said housing through said top wall opening, at least one of said heat exchanger ducts communicating with said flue, and said 65 one end wall having an opening adjacent its top in alignment with said heat exchanger ducts for educting air from the housing so that air discharged by said blower through the shroud initially impinges against the lower portion of the combustion chamber shell and said opposite end wall and thence passes upwardly toward the 70 75

upper portion of the combustion chamber shell and the top wall to be finally deflected generally horizontally along said heat exchanger to pass outwardly of said housing through the last mentioned opening.

2. A forced air ventilating heater as defined in claim 5, wherein the lower end of said combustion chamber shell is cut away in a region thereof facing said opposite end wall to form said opening for the supply of combustion air to the burner so that the flow of air created by said blower furnishes the combustion air for the 10 burner.
